[57] CLAIM

The ornamental design for a guitar bridge, as shown and described.

DESCRIPTION

FIG. 1 is a front view of a guitar bridge showing my new design;

FIG. 2 is a bottom end view of the guitar bridge of the present invention;

FIG. 3 is a back view of the guitar bridge of the present invention;

FIG. 4 is a top end view of the guitar bridge of the present invention; and,

FIG. 5 is a cross sectional view taken along line 5—5 of FIG. 1 of the guitar bridge of the present invention.

The broken lines shown in FIG. 5 are for illustrative purposes only and form no part of the claimed design.
